UNITED STATES PATENT OFFICE.

DAVID H. MacFALLS, OF NEW YORK, N. Y.

SAFETY RAZOR.

Application filed January 27, 1926. Serial No. 84,220.

The razor of the present invention combines all of the safety of an ordinary safety razor with all of the ready manipulability and convenience in shaving at awkward angles of the straight razor. It is in effect a straight razor made safe with the head of the razor so adjustable relative to the handle that any desired shaving angle may be obtained and the usual barber stroke permitted.

10 An object of the invention is to provide a safety razor combining the above noted advantages with simplicity and ruggedness of construction.

15 A further object is to provide a safety razor from which the blade may be readily removed and replaced for purposes of cleaning, honing and sharpening, etc.

20 A still further object is to provide a safety razor in which the shaving head is automatically locked in all of its various adjusted relations to the handle, and which may be manufactured with comparative economy.

25 With the above noted and other objects in view, the invention consists in certain novel features of construction and combinations and arrangements of parts, as will be more fully hereinafter described and pointed out in the claims.

The invention may be better understood 30 from the following description in connection with the accompanying drawings, wherein—

Fig. 1 is a plan view of a razor embodying the present invention.

Fig. 2 is an edge view of Fig. 1.

35 Fig. 3 is a plan view of the blade holding guard plate disassembled from the handle and with the blade and spring removed.

Fig. 4 is a fragmentary view in side elevation of the handle.

40 Fig. 5 is a transverse sectional view on the line 5—5 of Fig. 3.

Fig. 6 is a fragmentary elevational view of the handle taken at right angles to Fig. 4.

45 In the drawings, I have used the reference character 10 to designate the blade supporting guard plate including a flat plate portion 11 of approximately segmental shape integral at its flat side with angular disposed blade guard portion 12, the latter being formed at its guard edge with a series of guard teeth 13. The side edges of the blade guard 12 are rolled over or turned inwardly at 14 to define a receiving channel 55 15 for the edges of a blade 16.

The cross sectional shape of the blade may

be best seen from Fig. 5 where it will be noted that the blade is of a cross sectional shape closely corresponding to the shape of an ordinary hollow ground straight razor. 60 The blade ends lie flatly under the members 14, and forward movement of the blade is limited by a stop 14^a turned downwardly from the forward or outer ends of members 14. 65

The razor handle 17 may be of various shapes, but in any event includes at one end an angularly disposed stud portion 18 carrying a polygonal rigid blade clamping head 19. The stud 18 projects from a flat shoulder 20 at the end of the handle. 70

The plate portion 10 is formed with an open ended slot 21 adapted to receive the neck 18. When this neck is accommodated by the slot 21, shoulder 20 and head 19 effectively prevent pivotal movement of the plate 11 in any direction except in a plane parallel to the plane of the shoulder 20. The handle will thus be disposed at all times in substantial parallelism with the shaving head. A 80 flat spring 22 having its ends suitably removably anchored as by the recessed or channel lugs 23 rising from the plate 10, bears against the head 19 and forces the latter against the rear side of blade 16, thereby forcing the blade home under the keepers 14. 85

The head 19 might be made of various polygonal shapes but I have found the most desirable shape to be hexagonal with the 90 lateral faces of hexagon disposed eccentrically relative to the neck or pivot 18. These faces have been numbered 19^a, 19^b, 19^c, 19^d, 19^e and 19^f. The face 19^d is disposed at the greatest distance from the pivot 18 and the face 19^e is disposed closest to the pivot. 95

When inserting the blade, handle 17 is rotated until the face 19^d is engaged by the spring 22 which forces the neck or stud 18 against the inner end of the slot 21. In this 100 position ample room is provided for insertion of the blade due to the relatively short distance between the center of the stud 18 and the face 19^a. When any of the other five faces of the head 19 are engaged by the 105 spring the opposite face of the stud will be urged into clamping relationship with the blade back as will be readily understood.

By virtue of this construction the shaving 110 head may be adjusted at five different angles relative to the handle. The adjustment is

effected in every instance simply by rotating the shaving head relatively to the handle. In every instance, the spring 22 acts automatically to lock the head in the desired position of adjustment relative to the handle.

From the foregoing description, it will be evident that the device of the present invention may be used substantially in the manner of a straight razor to obtain a barber's stroke, and due to the wide and varied range of adjustments possible, permits anyone skilled in the use of a straight razor to shave with ease and expedition.

If the user desires the ordinary safety razor stroke this may also be obtained by proper adjustment of the shaving head relative to the handle.

While I have illustrated one of the preferred embodiments of the invention, it will be understood that numerous changes and alterations might be made in the general form and arrangement of parts described, without departing from the invention. Hence I do not wish to limit myself to the details set forth, but shall consider myself at liberty to make such changes and alterations as fairly fall within the spirit and scope of the appended claims.

I claim—

30. 1. A safety razor including a shaving head and a handle disposed in plane approximately parallel to the plane of the head, said head and handle being pivotally connected, a blade removably associated with the head and automatically acting spring means for simultaneously locking said head and handle in various positions of pivotal adjustment and retaining the blade against displacement.
40. 2. A safety razor including a blade holding plate having a slot therein, a blade guard integral with the plate and adapted to receive a blade, a handle including a reduced portion pivotally and slidably mounted in said slot and a head portion bearing against the back of the blade to retain the latter in position.
50. 3. A safety razor including a blade holding plate having a slot therein, a blade guard integral with the plate and adapted to receive a blade, a handle including a reduced portion pivotally and slidably mounted in said slot and a head portion bearing against the back of the blade to retain the latter in position and spring means acting on the head to force the same against the blade.
60. 4. A safety razor including a blade holding plate having a slot therein, a blade guard integral with the plate and adapted to receive a blade, a handle including a reduced portion pivotally and slidably mounted in said slot and a head portion bearing against the back of the blade to retain the latter in position and spring means acting on the head to force the same against the blade.
65. 5. A safety razor including a blade holding plate having a slot therein, a blade guard integral with the plate and adapted to receive a blade, a handle including a reduced portion pivotally and slidably mounted in said slot and a head portion bearing against the back of the blade to force the same against the blade, said head being of polygonal shape offering a plurality of blade engaging faces.

5. A safety razor including a blade holding plate having a slot therein, a blade guard integral with the plate and adapted to receive a blade, a handle including a reduced portion pivotally and slidably mounted in said slot and a head portion bearing against the back of the blade to retain the latter in position and spring means acting on the head to force the same against the blade, said head being of irregular hexagonal shape offering a plurality of blade engaging faces.

6. A safety razor including a blade holding plate having a slot therein, a blade guard integral with the plate and adapted to receive a blade, a handle including a reduced portion pivotally and slidably mounted in said slot and a head portion bearing against the back of the blade to retain the latter in position and spring means acting on the head to force the same against the blade, said head being of irregular polygonal shape offering a plurality of blade engaging faces.

7. A safety razor including a blade holding plate having a slot therein, a blade guard integral with the plate and adapted to receive a blade, a handle including a reduced portion pivotally and slidably mounted in said slot and a head portion bearing against the back of the blade to retain the latter in position and spring means acting on the head to force the same against the blade, said head being of irregular polygonal shape offering a plurality of blade engaging faces spaced at different distances from the reduced pivotal portion of the handle.

7. A safety razor including a blade holding plate having a slot therein, a blade guard integral with the plate and adapted to receive a blade, a handle including a reduced portion pivotally and slidably mounted in said slot and a head portion bearing against the back of the blade to retain the latter in position and spring means acting on the head to force the same against the blade, said head being of irregular polygonal shape offering a plurality of blade engaging faces spaced at different distances from the reduced pivotal portion of the handle, said handle in one position of adjustment permitting unrestricted removal of the blade.

8. A safety razor including a blade holding plate having a slot therein, a blade guard integral with the plate and adapted to receive a blade, a handle including a reduced portion pivotally and slidably mounted in said slot and a head portion bearing against the back of the blade to retain the latter in position and spring means acting on the head to force the same against the blade, said head being of irregular polygonal shape offering a plurality of blade engaging faces spaced at different distances from the reduced pivotal portion of the handle, said handle in one position of adjustment permitting unrestricted removal of the blade and in all other positions of pivotal adjustment being spring pressed into clamping engagement with the blade, holding the blade securely in position for shaving.

9. A safety razor including a blade holding plate having a slot therein, a blade

guard integral with the plate and adapted to receive a blade, a handle including a reduced portion pivotally and slidably mounted in said slot and a head portion bearing against the back of the blade to retain the latter in position, a flat spring carried by the holding plate acting on the head to force the same into clamping engagement with the blade.

10 10. A safety razor including a plate having an angularly offset blade holding guard portion, channels at the edges of said portion receiving a hollow ground blade, means to limit the entering movement of the blade within the channels, a handle having a pivotal adjustment relative to the plate and including a head engageable with the back of the blade.

15 11. A safety razor including a plate having an angularly offset blade holding guard portion, channels at the edges of said portion receiving a blade, means to limit the entering movement of the blade with the channels, a handle having a pivotal and sliding connection with the plate and including a head engageable with the back of the blade, and a flat spring bearing against the head to hold the same against the blade.

20 12. A safety razor including a plate having an angularly offset blade holding guard

portion, channels at the edges of said portion receiving a blade, means to limit the entering movement of the blade with the channels, a handle having a pivotal and sliding connection with the plate and including a head engageable with the back of the blade, and a flat spring bearing against the head to hold the same against the blade, said head being irregular polygonal shape offering plurality of blade engaging faces.

25 13. A safety razor including a plate having an angularly offset blade holding guard portion, channels at the edges of said portion receiving a blade, means to limit the entering movement of the blade with the channels, a handle having a pivotal and sliding connection with the plate and including a head engageable with the back of the blade, and a flat spring bearing against the head to hold the same against the blade, channelled posts on the plate receiving the ends of the spring.

30 14. A device of the class described in claim 10, and wherein, when the handle is pivotally adjusted to the usual angle for shaving, it will be disposed approximately parallel to the plate of the blade, and the exposed concave face of the blade will ride flatly over the surface being shaved.
